UNITED STATES PATENT OFFICE.

ADALINE A. ROCKWELL, OF NEW YORK, N. Y.

DESIGN FOR RUCHES.

Specification forming part of Design No. 7,407, dated April 28, 1874; application filed April 20, 1874.
[Term of Patent 3½ years.]

To all whom it may concern:

Be it known that I, ADALINE A. ROCKWELL, of the city, county, and State of New York, have invented a Design for Ruches, of which the following is a specification:

The nature of my design is fully represented in the accompanying drawing, to which reference is made.

Figure 1 is a top view, showing the form or figure of the ruche in part, and Fig. 2 an end view of the same.

Similar letters of reference indicate corresponding parts.

A represents the body of the ruche, which is formed of a ruffle in loops *b*, having a ser-

pentine course, and presenting a series of flutes with rounded edges *c*, said flutes meeting below and spreading outward above. Within or between each alternate loop *b* is an independent duplex round-edged loop, *B*, having a stem-like trunk or base, *d*, and the facial presentation of which is transverse to the length of the ruche.

What I claim as my invention is—

The design for ruches, substantially as described, and shown in the annexed drawing.

A. A. ROCKWELL.
